APPARATUS FOR JOINING FABRIC

Daniel Wise, Reading, Pa.

Application October 1, 1956, Serial No. 613,111

1 Claim. (Cl. 112—152)

This invention relates to the novel modification of a sewing machine as well as to a new construction of presser foot employed. The novel method of securing two fabric portions and an intermediate joining strip to one another in one operation which may employ the apparatus of this application is claimed in a divisional application, Serial Number 674,003 filed July 19, 1957.

In many clothing manufacturing operations, particularly where relatively light materials are used as in the manufacture of underwear, it is necessary, in order to construct the garment, to join two portions of fabric to one another. In such construction the joined portion is obviously weaker than the remainder of the garment. In order to prevent untimely failure of the garment and to improve the wearing quality thereof, a reinforcing strip may be provided along the join so as to reinforce the weak portion. This construction is shown in the United States patent to Levy No. 560,296.

Conventionally, however, in order to carry out this construction, it has been necessary to first stitch the fabric portions together and then, after such stitching is performed, to sew the reinforcing strip along the joint or seam. Thus two separate and distinct operations have been required.

Under the present invention, on the other hand, the reinforcing strip is joined to the fabric portions and the portions are joined to one another in a single operation. Thus a considerable saving results in both labor and material and permits the garment produced to be sold at a lower price.

The modified sewing machine used to carry out this invention includes a supporting frame, a plurality of parallel vertically reciprocatingly movable needles, a folding device having a longitudinal guide channel narrowed at its terminal end, and a presser foot.

The presser foot itself is formed with a base portion which is disposed above the fabric portions to be joined together. The base portion is provided with an opening therein. A holding portion is above the base portion and is adapted to hold a fabric reinforcing strip slidably therewithin.

The invention will be further described by reference to the accompanying drawings which are a part of this specification. It is pointed out, however, that the specific form shown therein is merely illustrative and various changes and modifications may obviously be made within the spirit and scope of the invention disclosed.

Fig. 1 is a side perspective view of a sewing machine which has been modified to carry out the method of this invention and which shows the operation of such method.

Fig. 2 is a detail view of a portion of the presser foot which may be used in this invention.

Fig. 3 is a somewhat diagrammatic perspective view of two fabric portions secured to one another by a joining strip with the forward portion thereof in unsecured relationship so as to show the details of construction.

Fig. 4 is a sectional view through two fabric sections and a joining strip secured to one another in accordance

2

with this invention showing the details of construction.

Fig. 5 is a detail view of the following device used in this invention to fold the joining strip.

Fig. 6 is a detail perspective view of the presser foot of this invention and associated parts.

By reference to the drawings of the preferred modification of this invention and a detailed description thereof as set forth herebelow the invention will be further explained.

10 The sewing machine 10, which is preferably used to carry out the method of this invention, is formed with a supporting frame 26. The frame bears the conventional drive pulley 30 which in turn, by conventional linkage (not shown) vertically reciprocatingly moves the needle bar 24. A plurality of spaced parallel needles 23 are secured to needle bar 24. Each of needles 23 is formed with a conventional eye at its lower portion (not shown). Frame 26 is formed with a lower shelf portion 28. Beneath shelf portion 28 a longitudinally movable feed 20 (not shown) causes fabric to be moved in the direction of the arrow.

A conventional lower thread supply and a looper (both not shown) are disposed beneath shelf portion 28 as in the conventional sewing machine.

25 The face plate 11 of the sewing machine bears a bracket 12 which is secured thereto by screw 13. Bracket 12 bears an offset portion 15 at its forward portion which is adapted to support folder 14. Folder or guide 14 in turn rests upon projecting portion 16a of face plate 11.

30 Folder 14 is formed with two turned back portions 16 which form a fabric channel. At the lowermost portion of folder 14 two inwardly turned portions 18 are provided. The overturned portions 18 converge and the delivery end of the guide 14 is thus narrowed.

35 The presser foot 19 of this invention is provided with a central rear opening 27 within which the needles 23 move upwardly and downwardly. A pair of toe portions 25 are also provided at the front thereof. The bottom of said toe portions is springy by being spaced from the top portion. The foot 19 comprises two longitudinal sections, the under parts of which are springy and elastic and these sections are rigidly united, the space 27 being between the sections at the rear of the piece 19a.

40 Adjacent to opening 27 presser foot 19 is formed with loop 20 which is spaced from the top portion 21 of said presser foot. Loop 20 serves as a holding portion and slidably holds the fabric strip as will be subsequently explained. The loop 20 is borne by a part rigid with one side or section of the foot 19, and said part extends diagonally so that the loop 20 is maintained centrally in position over the space 29.

45 With the above apparatus as disclosed the method of this invention will now be explained.

50 A length of reinforcing strip 17 is drawn from a supply spool and passed through folder 14. The strip emerges from the bottom of folder 14 with a doubled portion 22. While in Figure 5 of the drawing, for clarity of illustration, the portion 22 is shown uppermost, in the operation of this invention, as shown in Fig. 3, this portion is on the lower surface.

55 The folded strip is then passed under loop 20 beneath needles 23 and within opening 27.

60 While this is being done two pieces of fabric to be joined 23a are disposed with edges abutting or nearly abutting beneath presser foot 19 which is in raised position. The pieces of fabric are placed side by side with one another and the folded strip 17 is disposed longitudinally in lapping position across the adjacent edges of the fabric pieces.

65 70 Presser foot 19 is then lowered and the sewing machine operated. The machine causes a row of stitches to be made between the folded strip 17 and the fabric portions

23a. These stitches are shown in Fig. 4 and are given the reference character 24a.

As the stitches are made the feed mechanism of the machine causes the fabric pieces to move in the direction of the horizontal arrow. Since the forward portion of the folded strip 17 has been secured across the seam between the two pieces of fabric 23 by the stitches 24a further movement of the pieces of fabric 23 in the direction of the horizontal arrow causes the strip 17 to be moved in the same direction thus pulling the strip into the folder as shown by the upper arrow. When the fabric 23a has passed beyond presser foot 19 the machine is stopped, the folded strip 17 cut off and the operation is then repeated.

I claim:

A sewing machine comprising, in combination, a supporting frame, a plurality of parallel vertically movable needles, a folding strip guide device angularly secured to said supporting frame with one end adjacent said needles and having at said end overturned converging edges adapted to deliver to said needles a doubled fabric strip with downwardly folded edges; a presser foot vertically movable in said frame, said presser foot comprising longitudinal sections each having an upper face and an elastic springy lower face, the sections being spaced from one another in direction of feed and on each side of said

needles to receive therebetween said folded fabric strip, the sections each having a forward toe portion adapted to engage an edge portion of one of a pair of fabric members supported edge to edge beneath said presser foot, an elongated transverse loop mounted on one of said longitudinal sections of said presser foot and extending across the space between said sections, and positioned below the delivery end of said guide device.
